CLAIM

The ornamental design for a pole-mountable security system, as shown and described.

DESCRIPTION

FIG. 1 is a front perspective view of a pole-mountable security system in accordance with the design;

FIG. 2 is a front perspective view thereof, shown in condition of use with a pole disclosed in broken lines to illustrate an environment;

FIG. 3 is a rear perspective view thereof, shown in condition of use with a pole disclosed in broken lines to illustrate an environment;

FIG. 4 is a front view of the pole-mountable security system of FIG. 1;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines represent environmental structure and form no part of the claimed design.
